[57] CLAIM

The ornamental design for a telephone interconnect system, substantially as shown.

DESCRIPTION

FIG. 1 is a top perspective view of a telephone interconnect system showing my new design;
FIG. 2 is a front elevation of said system;
FIG. 3 is a left side view of FIG. 1 of said system;
FIG. 4 is a right side view of FIG. 1 of said system;
FIG. 5 is a rear elevation of said system;
FIG. 6 is a top plan view of FIG. 1 of said system;
FIG. 7 is a bottom plan view of FIG. 5 and FIG. 6 of
said system.
